PLATFORM LAYING AND PLATFORM COVER
TURNING MACHINEJohn T. Lancaster, Newton, Mass., assignor to
United Shoe Machinery Corporation, Flemington, N. J., a corporation of New Jersey

Application May 1, 1950, Serial No. 159,213

15 Claims. (Cl. 12—1)

1

This invention relates to machines for use in the manufacture of shoes and it is herein disclosed as embodied in a machine for laying platform units upon the insoles, such as sock linings, of platform shoes and also for turning the platform covers of the shoes. These operations are performed upon partially completed platform shoes which may consist of sock linings, uppers, and platform covers united by stitching.

It is an object of this invention to provide a simple machine for readily and conveniently performing the above-mentioned operations.

In accordance with a feature of the invention, the illustrated machine is provided with a shoe support which is yieldable downwardly and with a plunger which presses a pre cemented platform unit down upon the pre cemented sock lining of the shoe to effect adhesion and also to move the shoe together with its support downwardly while suitably arranged tools turn the platform cover. As shown herein, the shoe support is normally held up by a spring and the plunger is operated by a treadle. The turning tools are thin plate-like members which will hereinafter be termed "horns" and these horns are assisted by tools engageable with the outside of the platform cover and operated by the shoe support in its downward movement.

These and other features of the invention will appear from the following detailed description of an illustrative embodiment of the invention, when considered in connection with the accompanying drawings, and will be pointed out in the appended claims.

In the drawings,

Fig. 1 is a side elevation of an illustrative machine embodying the invention, the machine being shown in its initial position;

Fig. 2 is a plan view showing the positions of the various parts of the machine at the completion of the cover turning operation;

Fig. 3 is a front elevation of the machine, partly in section;

Fig. 4 is a half-sectional rear elevation showing the turning instrumentalities at one side of the heel portion of the shoe at an intermediate stage of the cover turning operation;

Fig. 5 is a view similar to Fig. 4 showing the turning instrumentalities at the completion of the operation;

Fig. 6 is an angular view showing the turning instrumentalities on the side of the machine opposite to that shown in Figs. 4 and 5;

Fig. 7 is an angular view of a portion of the mechanism at the front of the machine;

2

Fig. 8 is a rear elevation of the machine, partly in section;

Fig. 9 is an angular exploded view showing a portion of the mechanism;

5 Fig. 10 is a view similar to Fig. 1, showing the positions of the various parts of the machine at the beginning of the cover turning operation, parts being shown in section;

10 Fig. 11 is a sectional view in side elevation of mechanism for automatically controlling the friction tools;

Fig. 12 is a sectional view in rear elevation taken on the line XII—XII of Fig. 11;

15 Fig. 13 is a sectional view in plan taken on the line XIII—XIII of Fig. 11; and

Fig. 14 is an angular view of a portion of the mechanism shown in Figs. 11, 12, and 13.

The illustrated machine has a shoe support in the form of a jack 20 (Figs. 1 and 10) upon which is secured an upstanding last pin 22 (Fig. 8 shows the entire pin; Figs. 1 and 10 show only the collar portion of the pin) and a toe rest 24 for supporting a shoe in inverted position. The shoe, as shown herein, consists of an upper U, a platform cover C, and an insole in the form of a sock lining S (Figs. 4, 5, and 8), all joined together by stitching and mounted upon a last L. The last pin 22 engages a thimble hole in the cone of the last L.

20 30 One of the functions of the machine is to press a platform P against the sock lining of the shoe, the adjoining surfaces of the platform and the sock lining having been precoated with cement to cause them to adhere upon pressure. Such pressure is applied by a treadle-operated plunger

35 or presser 26 (Figs. 1 and 10) having a heel plate 28 and a toe plate 30. The jack 20 yields downwardly under the force of the presser 26 until its downward movement is limited by a stop

40 45 (later to be described), whereupon the force of the presser is exerted positively against the platform. During the downward yielding movement of the jack 20, the platform cover C is turned by a plurality of blade-like members or horns 32, 34, 36, 38 (Figs. 1 and 10), 40 (see also Fig. 2), and 42 which enter between the platform cover C and the upper U as the shoe moves downwardly and which are themselves held against heightwise movement. The upper edges

50 45 of the horns are thin, but blunt enough to facilitate the rolling of the platform cover over these edges as it is being turned; and these edges are slightly bent out away from the shoe (as best shown on the horn 32, Fig. 1) to enable them to

55 clear the line of stitching at the base of the so-

called "crease" between the platform cover and the upper. Associated with the horn 32 and overlying it is a friction tool 44 which engages the outside of the platform cover C and which is urged upwardly as the shoe moves downwardly to assist in the turning of the platform cover. Similar friction tools 46, 48, 50, 52 and 54 are associated respectively with the horns 34, 36, 38, 40 and 42.

The jack 20 comprises a horizontal bar 56 (Figs. 1, 3, 8 and 10) extending lengthwise of the shoe and having adjacent to its heel end a split socket into which a depending shank 58 of the last pin 22 is clamped in a desired position of heightwise adjustment by a bolt 60 and nut 62. The bar 56 adjacent to its toe end is shaped to form a guideway (Fig. 3) for a slide 64 which can be clamped by a setscrew 65 in any desired position of longitudinal adjustment along the guideway. The slide 64 has a socket which engages a stem 68 depending from the toe rest 24. A setscrew 69 (Fig. 3) secures the stem 68 in any desired position of heightwise adjustment in its socket. The bar 56 is secured upon the upper end of a plunger 70 (Figs. 1, 9 and 10) which is slidable heightwise in a stationary sleeve 72 and is held against turning in the sleeve by a key 74. The sleeve 72 has a flange 76 which is secured by screws 78 upon the upper end of a frame or standard 80 which rests upon the floor. The plunger 70 is normally held up by a coil compression spring 82 which surrounds a stem 84 depending from the plunger 70. The lower end of the spring 82 abuts against an internal flange 86 on the sleeve 72 and the upper end bears against the lower end of the plunger 70. The upper position of the jack 20 under the influence of the spring 82 is determined by a stop 88 secured upon the lower end of the stem 84 and engageable with the bottom face of the sleeve 72. Downward movement of the jack 20 is limited by a shoulder 90 formed upon a boss depending from the bar 56 and engageable with the upper end of the sleeve 72. The jack 20 can be latched in an intermediate position by a latch 92 pivotally mounted upon a fulcrum pin 94 which is secured in the frame 80. The latch 92 engages the stop 88 to hold the plunger 70 down against the force of the spring 82. The latch 92 is urged into latching position by a coil compression spring 96 and can be released by a handle 98.

The presser 26 (Figs. 1, 2 and 10) as already mentioned, has a heel-engaging plate 28 and a toe-engaging plate 30. The toe-engaging plate is slidably guided in the presser for longitudinal movement of adjustment in accordance with the length of shoe to be operated upon and it is clamped in its adjusted position by a screw 100 threaded into the toe plate and extending through a slot 101 (Fig. 2) in the presser. Secured in the presser 26 is an upstanding pivot pin 102 (Fig. 10) which is journaled in a bearing formed in the end portion of an arm 104. A collar 106 on the upper end of the pin 102 engages the upper end face of the bearing and a boss 108 on the presser 26 engages the lower end face of the bearing to prevent heightwise movement of the presser 26 relative to the arm 104. A handle 110 extending from the collar 106 enables the operator to manipulate the presser by turning it about the axis of the pin 102 and also by swinging the arm 104 about an upright pin 112. The arm 104 has a bearing which engages the pin 112 and which has upper and lower end faces engageable with lugs 114 and 116 respectively ex-

tending from a sleeve 118 secured upon the upper end portion of a treadle rod 120. The pin 112, which serves as a pivotal support for the arm 104, is carried by the lugs 114 and 116. The sleeve 118 is secured upon the treadle rod 120 with provision for heightwise adjustment by a pair of clamping nuts 122 and 124 threaded upon the treadle rod. The treadle rod is normally held up by a coil compression spring 126 which surrounds it and which has its lower end abutting against a lug 128 on an L-shaped bracket 130 secured to the frame 80 and its upper end bearing against a collar 132 on the rod 120. The upwardly extending arm of the bracket 130 is channel shaped to loosely embrace the rod 120; and the upper portion of the bracket has formed in it guideways engaged by guide lugs 133 (Fig. 2) extending laterally from the sleeve 118 to guide and support the presser 26 in its operative downward movement.

The horn 32 (Figs. 1 and 10) operates upon the toe end of the platform cover C and it is dovetailed in a groove in a block 134 for heightwise adjustment with respect to the block; and the block is pivotally mounted for tilting movement of adjustment about a transverse horizontal screw 136 which can be tightened to clamp the block in adjusted position between two ears constituting an upward extension of an arm 138. The lower end portion of the horn 32 is notched to engage a head 140 of an adjusting screw which is threaded into the block 134 and which is manually turned to vary the heightwise adjustment of the horn. The lower end of the arm 138 is forked to form a pair of ears which are secured by set screws 142 (Fig. 7) to a horizontal transverse shaft 144 (see also Figs. 3 and 10) journaled in bearings formed upon arms 150 and 152 respectively of a bracket 154 secured upon a squared upper end portion 156 of the sleeve 72. Secured upon an end portion of the shaft 144 is a gear sector 158 which engages a worm 160 fixed on a horizontal longitudinally extending shaft 162 which is journaled in bearings 164 and 166 formed in an upstanding portion of the arm 152. The shaft 162 has a knurled head 163 (Figs. 1, 6, and 10) by which it can be turned. The worm 160 does not extend the full distance between the opposing end faces of the bearings 164 and 166 and the shaft 162 is permitted to slide as well as to turn in said bearings. A coil compression spring 168 surrounding the shaft 162 and interposed between the opposing end faces of the bearing 164 and the worm 160 urges the worm in a heelward direction tending to bring the heelward end face of the worm into engagement with the opposing end face of the bearing 166. It is evident that when no shoe engages the horn 32, the spring 168, acting through the gear 158, will urge the arm 138 heelward to an initial stopped position determined by the engagement of the worm 160 with the bearing 166 (as shown in Fig. 1) and that when a shoe is placed upon the jack and the jack is lowered to the position shown in Fig. 10, the upper of the shoe will cause the horn 32 to yield in a toeward direction as permitted by the spring. The horn 32 is thus held yieldingly by the spring 168 against the upper of the shoe to enable the horn to enter between the platform cover and the upper as the shoe descends. The initial position of the horn 32 can be adjusted toewardly or heelwardly by turning the knurled head 163.

The friction tool 44 (Figs. 1 and 10) is pivotally

mounted upon a pin 170 secured in the upper end portion of a stem 172 which is adjustably clamped by a screw 174 in a split bearing formed in the upper end of a lever 176. The stem 172 is inclined upwardly and heelwardly from its bearing in the lever 176. The lever 176 adjacent to its lower end (see also Fig. 7) is pivotally mounted upon a transverse horizontal pin 178 secured between a pair of ears on the forward end of a lever 180 which is fulcrumed for free rocking movement on the shaft 144 and extending between the ears formed by the forked lower end portion of the arm 133 (Fig. 7). A leaf spring 182 clamped in a split lug 183 on the lever 180 and acting upon the lever 176 normally maintains the friction tool 44 in a position determined by a cam 184 (see also Figs. 2 and 9) engaging a roll 186 on the lower end portion of the lever 176.

The cam 184 is mounted on a spider arm 188 of a bracket 190 (Figs. 7 and 9) which is rotatable about the axis of the sleeve 72 and which may be turned into and out of operative position by a handle 192. To provide for radial adjustment, the cam 184 is carried not directly by the spider arm 188 but by a dovetail slide 194 which is radially slideable in the spider arm and which has an interlocking extension 196 (Fig. 9) also slideable in the same guideway. Formed in the extension 196 is an arcuate slot 198 which is substantially coaxial with the spider bracket 190 and which is engaged by a roll 200 on a pin 202 secured in and depending from a slide 204. This slide 204 is dovetailed for longitudinal sliding adjustment in a guideway formed in an under portion of the bracket 154, such adjustment being effected through rack teeth 206 formed on the upper surface of the slide 204 and engaged by a gear sector 208 secured upon a shaft 210. The shaft 210 is journalled in bearings formed in the bracket arms 150 and 152 and it is operated by a link 212 the lower end of which is pivotally connected by a pin 214 to a gear sector 216 (to be mentioned later) secured by a pin 218 to the shaft. The upper end of the link 212 (Fig. 7) is pivotally connected by a pin 220 to a lug 222 extending from the arm 136. It is evident that as the shaft 162 is turned to adjust the horn 32 a corresponding opposite adjustment of the cam 184 will be effected through the linkage and gears above described. The cam 184 acts upon the lever 176 below the pin 178, and hence the cam is adjusted in a direction opposite to that of the horn 32 in order that the adjustments of the horn 32 and the friction tool 44 will take place in the same direction.

The bracket 190 consists of a central boss from which extends the spider arm 188 and from which also extend five other spider arms (Fig. 2) later to be described. This boss 190 rests upon the upper surface of the flange 76 (Figs. 9 and 10) and is rotatable about the sleeve 72. The operative surface of the cam 184 is not circumferential but is spiral to enable the operator as he moves the handle 192 counterclockwise (as viewed from above) to bring the cam from an out-of-the-way position into an operative position wherein it engages the roll 186 and swings the friction tool 44 into an initial position wherein it will be out of the way of a shoe which is to be placed upon the jack 20. After the shoe has been placed upon the jack, and the jack has been lowered to the position shown in Fig. 10, the operator turns the spider in a clockwise direction to release the friction tool which, under the in-

fluence of the spring 182, will come yieldingly into engagement with the exposed surface of the platform cover.

The lever 180 is fulcrumed upon the shaft 144 and can rock with respect thereto. The end of the lever 180 opposite to the end which carries the pin 178 has mounted therein a pin 224 (Fig. 7) which carries an antifriction roll 226 (Figs. 1, 7 and 10). Depending from the bar 56 is a lug 228 having an under surface which, when the jack 20 descends, engages the roll 226 and swings the lever 180 in a clockwise direction to raise the friction tool 44. A tension spring 230 having its lower end anchored to a stationary pin 232 (later to be described) and its upper end hooked to the forward portion of the lever 180 holds the lever in an initial position (Fig. 1) determined by a stop (not shown). When the jack 20 descends and the lug 228 engages the roll 226 (Fig. 10), the spring 230 will hold the roll up yieldingly against the lug. The distances between the shaft 144 and the pins 178 and 224 respectively are substantially equal and it is evident, therefore, that as the jack 20 descends the friction tool 44 will rise at a speed substantially equal to that of the descending shoe and thereby urge the outer portion of the platform cover C upwardly while the platform cover is being drawn down over the upper edge of the horn 32.

The horn 34 (Figs. 6 and 10) operates upon one side of the platform cover at the forepart of the shoe. It has a depending cylindrical shank 234 which turns freely in a socket 236 formed in the upper end portion of a bar 238. A tension spring 240 having its upper end hooked to the horn 34 and its lower end anchored to the bar 238 holds the shank 234 down in its socket and also holds the horn in a neutral or initial angular position about the axis of its shank, from which angular position the horn can readily turn to conform to the direction of that portion of the shoe surface which it engages. On the lower portion of the bar 238 is a hub 242 which is slidably keyed upon a horizontal shaft 244 extending lengthwise of the shoe and having a keyway 246. The shaft 244 is journaled in three bearings 248 (Fig. 6), 250, and 252, the bearing 248 being integral with a lug 254 extending laterally from the bracket arm 152, and the bearings 250 and 252 being integral respectively with arms 256 and 258 extending from a bracket 260 (see also Fig. 7) secured to a lateral face of the squared upper portion 156 of the sleeve 72. The shaft 244 is held against axial movement in its bearings by a retaining collar 262 secured upon its rear end and a hub 264 secured upon its forward end. Depending from the hub 264 is a crank arm 266 (Figs. 3 and 7) having in its lower end a slot 268 (Fig. 1) which fits loosely over the pin 232 (already mentioned). This pin 232 extends through, and is fixed to, the bracket arms 150 and 152. Surrounding the pin 232 and interposed between the bracket arm 152 and the crank arm 266 is a coil compression spring 270 which urges the crank arm outwardly as far as permitted by a knurled stop nut 272. It is evident that, in the absence of a shoe against the horn 34, the spring 270 will cause the horn to assume a position determined by the adjustment of the nut 272, and that, when a shoe is placed upon the jack and the jack is depressed, the spring 270 will shorten and permit the horn to yield outwardly as it presses against the upper of the shoe in a position to enter between the upper and the platform cover of the shoe.

The horn 34 can be adjusted forwardly and rearwardly in accordance with the length of the shoe and, for convenience, this adjustment is effected automatically by the forward and rearward adjustment of the horn 32. To this end the hub 242 has an extension 274 (Figs. 6 and 9), on the under side of which are formed rack teeth which intermesh with teeth on a gear sector 276 secured by a pin 278 to the shaft 210. Inasmuch as the hub 242 is free to slide along the shaft 244, it is evident that the turning of the shaft 210 resulting from the adjustment of the horn 32 will serve to effect a similar adjustment, through the gear sector 276 and the rack extension 274, of the horn 34.

The friction tool 46 (Fig. 6) is pivotally mounted upon a horizontal pin 280 with limited freedom of heightwise swinging movement. The pin 280 is carried by an ear extending up from a short cylindrical rod 282 which can turn within a socket 284. A tension spring 286 anchored to the socket 284 and hooked to the rod 282 holds the rod down in its socket and also holds it in a neutral or initial angular position about its axis. The friction tool 46 can thus yield about two different axes to conform to the general plane of that portion of the shoe which it engages. The socket 284 constitutes the upper end portion of a bar 288 having, at its lower end, a hub 290 which is slidably keyed upon a horizontal shaft 292 extending parallel to the shaft 244. The shaft 292 is journaled in bearings 294, 296 and 298 carried by a rocking frame comprising a longitudinal bar 300 and rocker arms 302 and 304. suitable collars 306 and 308 on the end portions of the shaft 292 hold the shaft against axial movement. The rocker arms 302 and 304 have hubs 310 and 312 by which they are pivotally mounted for swinging movement upon the shaft 244.

A torsion spring 314 acting on the shaft 292 to urge the friction tool 46 toward the shoe is normally opposed by a cam mechanism which serves to hold the friction tool in an initial position. This mechanism comprises a cam 316 (Figs. 2 and 9) upon the outer end of a spider arm 318 which is integral with the spider bracket 190. The operating surface of the cam 316 is spiral with respect to the axis of the spider bracket 190, and it acts upon a cam roll 320 (Fig. 6) which is idly rotatable upon the lower end portion of a crank arm 322 depending from a hub 324 secured by a setscrew 326 to the shaft 292. Thus, when the handle 192 is moved to turn the spider bracket 190 clockwise, the friction tool 46 as well as the friction tool 44 will be released, and both friction tools under the influence of their respective springs will come yieldingly into engagement with the exposed surface of the platform cover.

The friction tool 46 is moved operatively up, while in yielding engagement with the platform cover, by mechanism comprising a lever 328 (Fig. 6) freely fulcrumed upon the shaft 244. The outer end of the lever 328 is integral with the bar 300, and the inner end carries an anti-friction roll 330. A torsion spring 334 normally holds the lever 328 in an initial position wherein the roll 330 is up and the friction tool down, this initial position being determined by a stop (not shown). When the jack 20 is lowered, a lug 332 on the jack will first engage and then depress the roll 330, thereby raising the friction tool.

Adjustment of the position of the friction tool 46 (Fig. 6) towardly or heelwardly, in accord-

5 ance with the size of the shoe, is effected automatically by a pair of arms 336 extending out from the bar 238 and embracing the bar 288 to cause the keyed hub 290 to slide along the shaft 292 in accordance with the forward and rearward adjustment of the horns 32 and 34 as previously described.

10 The horn 36 (Figs. 6 and 8) operates upon the platform cover at one side of the heel portion of the shoe. It has a depending flat shank 338 which is slidably mounted for heightwise adjustment in a block 340 having a suitable guideway for that purpose. A setscrew 342 (Fig. 8) holds the shank 338 in adjusted position. The block 15 340 is pivotally mounted for tilting movement of adjustment upon a horizontal clamping screw 344 carried on the upper end of a lever 346 having a hub 348 whereby the lever is freely fulcrumed upon the shaft 244. The lever 346 has a forked 20 extension 350 below the hub 348 and embracing a transverse pin 352 (see also Fig. 8). A bracket 25 354 (see Fig. 9) has two rearwardly extending arms 356 and 358 through which the transverse pin 352 extends and by which it is supported. A coil compression spring 360 surrounding the pin 352 and interposed between the bracket arm 358 and the lever extension 350 urges the lever extension outwardly to a stopped position determined by a knurled nut 362 threaded on the outer end portion of the pin 352. When the jack 20 with a shoe thereon descends, the horn 36, the initial position of which is determined by the stop nut 362, can yield outwardly and the horn will be pressed against the upper of the 30 shoe by the spring 360.

35 The friction tool 48 is mounted in an arcuate guideway formed in a block 364 and having a horizontal axis, the friction tool having a limited free tilting movement about said axis. A stop screw 365 in the block 364 engages a slot 40 in the friction tool 48 to retain the friction tool in its guideway. The block 364 has a depending cylindrical shank 366 which can turn within a socket 368, a tension spring 370 being provided to hold the shank down in its socket and also to 45 hold the shank in an initial angular position from which it can turn to conform to the plane of that portion of the shoe surface which it engages. The socket 368 is formed upon the upper end portion of a lever 372 having a hub 374 whereby the lever is freely fulcrumed upon the shaft 292. An arm 376, integral with the hub 374 and depending therefrom, carries a cam roll 378 which cooperates with a cam 380 (Figs. 2 and 9) on the end of a spider arm 382 integral with the spider bracket 190. A leaf spring 384 mounted on the rocker arm 304 urges the lever 372 inwardly to cause the friction tool 48 to press yieldingly against the platform cover. The operation of the cam 380 in holding the friction tool 48 in its initial position and in releasing it therefrom is similar to the operations of the cams 184 and 316, already explained. The operative upward movement of the friction tool 48 results from the upward movement of the shaft 292 upon which the hub 374 is mounted.

50 The horn 38 (Figs. 1 and 10) operates upon the platform cover at the heel end of the shoe. It has a depending shank 386 which is heightwise adjustable in a slot formed in a block 388, the shank being secured in adjusted position by a setscrew 390. The block 388 constitutes the upper portion of a lever 392 which is freely fulcrumed on a transverse pin 394 extending through and 55 secured in the bracket arms 356 and 358. The 60 65

lever 392 has a downward extension 396 depending below the pin 394, and this extension has an opening which loosely surrounds an eye bolt 398 extending lengthwise of the shoe and having its eye portion fitted around and supported by the pin 352 (Fig. 8). A coil compression spring 400 (Fig. 1) surrounding the eye bolt 398 and interposed between the lever extension 396 and a shoulder on the stationary bracket 354 normally holds the lever 392 in an initial position with the extension against a stop nut 402 threaded upon the rear end portion of the eye bolt. When the jack 20 with a shoe thereon is depressed, the horn can yield rearwardly while pressing against the shoe upper as the spring 400 shortens.

The friction tool 50 (Figs. 1 and 10) is mounted for limited tilting movement upon a transverse pin 404 carried by a pair of ears on the upper end of a lever 406. This lever 406 is fulcrumed upon a transverse pin 408 secured in and extending across a pair of ears formed on the rear end of a lever 410 which is fulcrumed at its mid-point on the transverse pin 394. As shown in Figs. 8 and 9, the lever 392 is branched or divided to provide an opening through which the lever 410 extends at the locality in which both levers are fulcrumed on the pin 394. The forward end of the lever 410 (Fig. 1) carries an antifriction roll 412 which is engaged by an abutment 414 on the heel end of the bar 56 when the jack 20 descends. A torsion spring 416 surrounding the pin 394 urges the lever 410 in a clockwise direction as seen in Figs. 1 and 10 to hold the roll 412 yieldingly against the descending abutment 414 or up in a limiting position determined by a stop (not shown) when the jack 20 is up in its initial position. A leaf spring 418 secured in the lever 410 and pressing against the lever 498 urges that lever forward toward the heel end of the shoe to an initial position determined by a cam 420 which is engaged by a roll 422 on an arm 424 integral with the lever 406 and depending below the fulcrum pin 408. The cam 420 is carried by a spider arm 426 which is secured to the spider bracket 190 by screws 428 (Figs. 1 and 8), the cam being releasable by the handle 192 to permit the spring 418 to urge the friction tool 50 yieldingly against the platform cover. The operation of the friction tool 50 is similar to the operations of the friction tools 44, 46, and 48, already described.

The horn 40 and the friction tool 52, as shown in Figs. 2, 4, 5, and 8, are respectively symmetrical to the horn 36 and the friction tool 48; and, moreover, all the supporting and operating members associated with the horn 40 and the friction tool 52 are symmetrical to corresponding members associated with the horn 36 and the friction tool 48. Said corresponding members, therefore, will not be described further; and where they appear on the drawings they will be indicated by primed reference numerals corresponding to the unprimed reference numerals of the members to which they are symmetrical.

The horn 42 and the friction tool 54 (Figs. 2 and 8) are respectively symmetrical to the horn 34 and the friction tool 46; and, moreover, except as below noted, all the supporting and operating members associated with the horn 42 and the friction tool 54 are symmetrical to corresponding members associated with the horn 34 and the friction tool 46. Such corresponding members will not be described further, and those which appear in the drawings will be indicated by primed reference numerals corresponding to the

unprimed reference numerals of the members to which they are symmetrical.

The exception mentioned in the foregoing paragraph concerns the adjusting mechanism 5 operated by the link 212 (Fig. 1). Only one such link is needed, and it is conveniently connected to the gear sector 276' (Figs. 3 and 9) rather than to the gear sector 276.

In operating the machine as so far described, 10 the shoe is placed upon the jack 20 and the platform P is placed by hand upon the sock lining. All parts of the machine are in their initial positions, the presser 26 being up and in an out-of-the-way position to one side of the shoe. The operator now grasps the handle 110 and swings the presser 26 about the axes of the pins 102 and 112 to position the presser and center it above the shoe as shown in Fig. 1. He then depresses the treadle, causing the heel plate 28 and the toe plate 30 to descend and engage the platform P. Continued lowering of the treadle causes the spring 82 to yield and permit the shoe and the jack 20 to descend from their initial positions. As the shoe descends, various localities 25 of the upper U will engage the horns 32, 34, 36, 38, 40, and 42, causing their springs to yield while maintaining the horns pressed against the upper so as to enter within the platform cover C. The operator continues to depress the treadle 30 until the jack 20 has come down far enough for the latch 92 to snap over the stop 88 and hold the jack down, as shown in Fig. 10; at this point he stops further depression of the treadle while maintaining enough pressure on it to hold the 35 presser 26 down against the platform P. The upper edges of the horns will now be substantially in contact with the base of the "crease" between the platform cover C and the upper U, in which positions they will be ready to begin 40 the turning operation; and the rolls 226, 330, 412, and 330' will be in substantial engagement with their respective abutments on the jack 20. While the jack 20 is thus latched in the position 45 shown in Fig. 10, the operator swings the handle 192 clockwise (as seen from above) to release all the friction tools 44, 46, 48, 50, 52, and 54 from the cams which hold them back away from the shoe. Upon such release, the various springs 50 associated with these friction tools will urge the friction tools yieldingly against the exposed surface of the platform cover. The operator then depresses the treadle further. Now, as the shoe descends, the platform cover will turn over the upper edges of the horns from the wrong-side-out position in which it is shown in Figs. 1 and 55 10 to an upstanding position wherein it is right side out; and the descending jack will force the rolls 226, 330, 412, and 330' down, thereby forcing the friction tools 44, 46, 48, 50, 52, and 54 60 up and causing them to aid the horns by easing the platform cover up over the edges of the horns (see Figs. 4 and 5). Since the levers which transmit motion from the rolls to the friction tools are all fulcrumed at their mid-points, the 65 friction tools will move up at the same speed as that at which the edge of the platform cover which is attached to the shoe moves down, the friction tools thus working in continuous co-operation with descending jack to turn the platform cover.

All the while that the shoe is descending, the platform is pressed against the sock lining with a yielding pressure depending upon the strength of the spring 82. This pressure causes a preliminary setting of the cement with which the

adjoining faces of the platform and the sock lining have been coated.

Before the jack 20 has descended far enough for the shoulder 90 to engage the top surface of the squared upper end portion 156 of the sleeve 72 and thus positively stop the downward movement of the jack 20, the platform cover has been completely turned. Now, when the downward movement of the jack is thus stopped, the pressure exerted by the operator on the treadle will be transmitted positively through the platform and against the sock lining, greatly strengthening the preliminary adhesive bond already mentioned and insuring a firm and dependable attachment of the platform.

The operation is now complete, and the operator releases the treadle while holding back the latch 92 to let the various parts of the machine return to their initial positions. He then swings the handle 192 counterclockwise to cause the friction tools to be withdrawn from the shoe into out-of-the-way positions. He then grasps the handle 110 and swings the presser 26 to one side, and removes the shoe from the jack.

To adjust the machine for any particular type of shoe, the knurled head 163 is turned to bring the horns 32, 34, and 42 and their cooperating friction tools 44, 46, and 54 to their proper positions lengthwise of the shoe. The toe rest slide 64 also is adjusted along the bar 56 bringing it into proper position with respect to the length of the shoe, and the toe rest support stem 68 is adjusted heightwise in its socket to insure that the upper edges of the horns 34 and 42 will be at the base of the "crease" between the platform cover C and the upper U when the shoe has been depressed to the position shown in Fig. 10. The shank 58 of the last pin 22 is then adjusted heightwise in its socket to a position which will insure an even distribution of pressure between the heel plate 28 and the toe plate 30 when the treadle is depressed. The remaining horns 32, 36, 38, and 40 are then adjusted to bring their upper edges at the base of the said "crease" when the shoe occupies the position shown in Fig. 10. Inasmuch as the heightwise positions of the friction tools are not critical, no provision for their heightwise adjustments is necessary.

Adjustment of the initial position of the horn 34 widthwise of the shoe is effected by turning the nut 272; and a similar adjustment of the horn 42 is effected by turning a nut (not shown) symmetrically related to the nut 272. Adjustment of the initial position of the horn 36 widthwise of the shoe is effected by turning the nut 362; and a similar adjustment of the horn 40 is effected by turning the nut 362'. Adjustment of the initial position of the horn 38 lengthwise of the shoe is effected by turning the nut 402.

Automatic operation of the friction members 44, 46, 48, 50, 52, and 54 by downward movement of the shoe supporting jack 20 can be effected by additional mechanism shown in Figs. 11 to 14 inclusive and now to be described. Such mechanism comprises an antifriction roll 430 positioned between two flanges 432 depending from the spider arm 426, the roll 430 acting upon one of the flanges to turn the spider with its cams 184, 316, 380, 420, 380', and 316' in one direction and acting upon the other flange to turn the spider and cams in the opposite direction. One of the flanges 432 has a lug 433 engageable with the roll 430 and extending into the space between the flanges to avoid lost motion between the roll and the flanges. The roll

430 is freely rotatable upon a pin 434 unstanding from a rocker arm 436 which has a hub 438 secured upon the upper end of an upright rockshaft 440 journaled in a bearing formed in the stationary bracket 130. A thrust collar 442 on the rockshaft 440 cooperates with hub 438 to hold the rockshaft against the heightwise movement, the thrust collar and the hub bearing against lower and upper surfaces on the stationary bracket 130. Secured upon the lower end of the rockshaft 440 is a hub 444 from which extends a rocker arm 446 having a cam roll 448 mounted for free rotation upon a pin 449 at its outer end. Surrounding the rockshaft 440 is a torsion spring 450 having its upper end anchored in the stationary frame 80 and its lower end secured to the rocker arm 446, the tendency of this spring being to urge the rockshaft 440 and its rocker arms in a counterclockwise direction (as seen from above).

The rockshaft 440 is operated by a release cam 452 and a restoring cam 453, both cams being movable with the stem 84 and engageable with the cam roll 448. The release cam 452, which serves to hold the rockshaft 440 in an initial position of rotation until the stem 84 has descended to a predetermined level and then suddenly to release the rockshaft to the action of the torsion spring 450, is slidably heightwise in a guideway formed in a block 454 integral with the stop 88. A cover plate 456 secured to the block 454 retains the cam 452 within the guideway. Interposed between the bottom of the guideway and the lower end of the cam 452 is a compression spring 458 surrounding a stem 460 which depends from the cam and slides through a bore in the bottom of the guideway, the compression spring serving yieldably to hold the cam up in a normal position determined by a stop nut 462 on the lower end of the stem. The upper portion of the cam 452 extends above the top of the block 454 and has a vertical restraining surface 464 (Fig. 14) engageable with the cam roll 448, a horizontal surface 466 along which the cam roll 448 travels under the influence of the torsion spring 450, and a vertical surface 468 serving as a stop to limit the movement of the cam roll under the influence of the torsion spring. As the shoe support 20 and with it the block 454 descend from their initial positions, the restraining surface 464 holds the cam roll 448 in opposition to the torsion spring 450 until the horizontal surface 466 permits the torsion spring to swing the cam roll into a position determined by the stop surface 468, such action of the torsion spring serving, through the roll 430, to swing the spider arms in a clockwise direction to release the friction members 44, 46, 48, 50, 52, and 54 to the actions of their individual springs whereby the friction members are moved yieldably into engagement with the platform cover C. The releasing operation of the cam 452 is so timed as to take place when the shoe supporting jack 20 has descended to the position shown in Fig. 10 and the cover turning operation is about to begin.

After continued depression of the treadle has brought the jack 20 to its lowest point and the operation upon the shoe has been completed, pressure upon the treadle is released and the jack is permitted to rise under the influence of its spring 82. As the block 454 thus rises, the release cam 452 will rise with it until the horizontal surface 466 encounters the cam roll 448, checking the upward movement of the cam and causing the spring 458 to be compressed. To

reset the release cam 452, the restoring cam 453 (which constitutes an upward extension of the cover plate 456) has an inclined surface 470 (Fig. 14) engageable, as the restoring cam rises, with the cam roll 448 to push the cam roll across and out of the way of the horizontal surface 436 and thus permit the compression spring 458 to return the release cam to its normal position, with the cam roll against the vertical restraining surface 464. The restoring cam, in pushing the cam roll 448 across the horizontal surface 436, also reloads the torsion spring 450. A flange 472 on the restoring cam 453 affords additional support to the release cam 452 against the pressure of the cam roll 448.

It is evident that on a machine equipped with the automatic mechanism just described, the latch 92 together with the handle 98 and its associated parts, and also the handle 192, are unnecessary and, if desired, can be omitted; and that the automatic mechanism enables the machine to perform its complete operation upon a single continuous depression of the treadle.

Having described my invention, what I claim as new and desire to secure by Letters Patent of the United States is:

1. In a machine for use in the manufacture of shoes, a support for a partially completed platform shoe having an insole and an unturned platform cover, means for pressing a platform unit against the insole to cause pre cemented surfaces of the platform unit and the insole to adhere, means acting upon the shoe support for yieldingly opposing the pressing means while permitting the pressing means to move the shoe and its support heightwise, a horn engageable with the platform cover to turn the platform cover as the shoe is thus moved heightwise, and a spring for yieldingly holding the horn against the outside of the shoe while the platform cover is being turned.

2. In a machine for use in the manufacture of shoes, a support for a partially completed platform shoe having an insole and an unturned platform cover, means for pressing a platform unit against the insole to cause pre cemented surfaces of the platform unit and the insole to adhere, means acting on the shoe support for yieldingly opposing the pressing means while permitting the pressing means to move the shoe and its support heightwise, means engageable with the platform cover to turn the platform cover as the shoe is thus moved heightwise, and a stop for holding the shoe support positively against the force of the pressing means when the turning of the platform cover has been completed, said stop thereby enabling the pressure between the platform unit and the insole to be increased and thereby complete the adhesion of each to the other.

3. In a machine for use in the manufacture of shoes, a support for a partially completed platform shoe having an insole and an unturned platform cover, a guideway in which the shoe support is movable heightwise of the shoe, a presser engageable with a platform unit which has been placed upon the insole, means for forcing the presser against the platform unit to cause pre cemented surfaces of the platform unit and the insole to adhere, a spring acting on the shoe support to oppose the pressure applied by said forcing means, a horn supported against heightwise movement and engageable with the platform cover to turn the platform cover as the shoe support moves along the guideway in re-

sponse to the pressure of the forcing means, which movement of the shoe support is permitted by the yielding of the spring, a second spring urging the horn in a horizontal direction toward the shoe, and an adjustable stop against which the second spring holds the horn in an initial position from which the horn can yield when engaged by the shoe.

4. In a machine for use in the manufacture of shoes, an upstanding last pin for supporting an inverted last on which is mounted a partially completed platform shoe having an insole and an unturned platform cover, a rest for supporting the forepart of the shoe and last, a common support for the last pin and the rest, a guideway in which the support is movable heightwise, a plunger engageable with a platform unit which has been placed upon the insole, means for forcing the plunger down against the platform unit to cause pre cemented surfaces of the platform unit and the insole to adhere, a spring acting on said support to oppose the pressure applied by the forcing means, and a plurality of horns supported against heightwise movement and engageable within the platform cover to turn the platform cover as said support moves down its guideway in response to the pressure applied by the plunger.

5. In a machine for use in the manufacture of shoes, an upstanding last pin for supporting an inverted last on which is mounted a partially completed platform shoe having an insole and an unturned platform cover, a rest for supporting the forepart of the shoe and last, a common support for the last pin and the rest, a guideway in which the support is movable heightwise, a plunger engageable with a platform unit which has been placed on the insole, treadle operated means for forcing the plunger down against the plunger down against the platform unit to cause pre cemented surfaces of the platform unit and the insole to adhere, a spring acting on said support to permit the support to yield and thereby limit the initial pressure applied by the forcing means, a horn supported against heightwise movement and engageable within the platform cover to turn the platform cover as the platform unit and the shoe are forced down by the plunger, and a stop for limiting the downward movement of the common support and holding it positively against the pressure applied by the forcing means and thereby completing the adhesion between the platform cover and the insole.

6. In a platform cover turning machine, an upstanding last pin for supporting an inverted last on which is mounted a partially completed platform shoe having an unturned platform cover, a rest for supporting the forepart of the shoe and last, a common support for the last pin and the rest, a guideway in which the support is movable heightwise, means for exerting downward pressure against the shoe to move the shoe and the support down in a path determined by the guideway, a spring normally holding the support up and yieldable downwardly to the pressure exerting means, a horn engageable within the platform cover at each end of the shoe, means for holding the horns up to enable them to turn the platform cover as the shoe moves down, a friction tool associated with each horn and engageable with the outer surface of that portion of the platform cover which overlies its associated horn, and connections through which the support in its downward movement causes the friction tools to move up in engagement with

the platform cover to assist the horns in turning the platform cover.

7. In a platform cover turning machine, a support for a partially completed platform shoe having an unturned platform cover, a guideway in which the shoe support is movable heightwise of the shoe, a spring normally holding the support in an initial position in its guideway, means for moving the shoe and the shoe support in a path determined by the guideway, a horn held against heightwise movement and engageable within the platform cover, said horn having an operative edge over which the platform cover must turn as the shoe is thus moved from its initial position, a friction tool engageable with the outer surface of that portion of the platform cover which overlies the horn, a spring urging the friction tool against the platform cover, means for moving the friction tool to cause it to push the platform cover toward the operative edge of the horn and thereby assist the horn in turning the platform cover, releasable means normally opposing the second-mentioned spring to hold the friction tool in an out-of-the-way position away from the platform cover, and a latch for holding the shoe support in an intermediate position in its guideway to enable the operator to release the friction tool to the operation of its spring after the horn has entered within the platform cover.

8. In a platform cover turning machine, a support for a partially completed platform shoe having an unturned platform cover, a guideway in which the shoe support is movable heightwise of the shoe, means for exerting pressure upon the shoe to cause the shoe support to move along its guideway, a plurality of horns held against heightwise movement and engageable within the platform cover, each horn having an operative edge over which the platform cover must turn as the shoe is thus moved, a friction tool associated with each horn and engageable with the outer surface of that portion of the platform cover which overlies its associated horn, means for yieldingly holding the friction tools in operating positions against the platform cover, means for operating the friction tools to cause them to push the platform cover toward the operative edges of their associated horns and thereby to assist the horns in turning the platform cover, and a common means for moving the friction tools from their operating positions to out-of-the-way positions wherein they avoid interference with a shoe which is to be placed upon or removed from the support.

9. In a platform cover turning machine, a plurality of tools engageable within an unturned platform cover of a partially completed platform shoe at spaced localities about the periphery of the shoe, each tool having an operative edge over which the platform cover is to be turned, means for effecting relative movement between the shoe and the tools to cause the platform cover to be turned over the operative edges of the tools, a friction tool associated with each of the first-mentioned tools and engageable with the outer surface of the platform cover, a spring for holding each friction tool in operating position against the platform cover, means for operating the friction tools to cause them to push the platform cover toward the operative edges of the first-mentioned tools and thereby assist the first-mentioned tools in turning the platform cover, and cam operated mechanism for simultaneously

moving the friction tools from operating positions to out-of-the-way positions.

10. In a platform cover turning machine, a support for a partially completed platform shoe having an insole and an unturned platform cover, a pair of members engageable with opposite surfaces of the platform cover for turning the platform cover, means for causing one of said turning members to press the platform cover against the other turning member, means for effecting relative movement between the shoe and the turning members to cause the platform cover to be turned, and interconnected means for simultaneously adjusting the positions of said turning members lengthwise of the shoe.

11. In a platform cover turning machine, a support for a partially completed platform shoe having an insole and an unturned platform cover, a horn engageable within the platform cover, a friction tool engageable with the outer surface of that portion of the platform cover which overlies the horn, a spring for pressing the friction tool against the platform cover, means for effecting relative heightwise movement between the shoe, the horn, and the friction tool to cause the platform cover to be turned over the horn, and interconnected means for simultaneously adjusting the positions of the horn and the friction member lengthwise of the shoe.

12. In a platform cover turning machine, a support for a last on which is mounted a partially completed platform shoe having an insole and an unturned platform cover, a horn engageable within the platform cover at the toe end of the shoe, a pair of horns engageable within the platform cover at the respective sides of the forepart of the shoe, a plurality of friction tools cooperating respectively with the horns, each friction tool being engageable with that portion of the platform cover which overlies its associated horn, a spring for pressing each friction tool against the platform cover, means for effecting relative heightwise movement between the shoe, the horns, and the friction tools to cause the platform cover to be turned over the horns, and interconnected means for simultaneously adjusting the positions of said horns and said friction tools lengthwise of the shoe to adapt them for operation upon shoes of different lengths.

13. In a platform cover turning machine, a support for a partially completed platform shoe having an unturned platform cover, a guideway in which the shoe support is movable heightwise of the shoe, means for exerting pressure upon the shoe to cause the shoe support to move along its guideway, a horn at each end of the shoe held against heightwise movement and engageable within the platform cover, each horn having an operative edge over which the platform cover must turn as the shoe is thus moved, a friction tool associated with each horn and engageable with the outer surface of that portion of the platform cover which overlies its associated horn, means for operating the friction tools to cause them to push the platform cover toward the operative edges of their associated horns and thereby to assist the horns in turning the platform cover, and a common means for adjusting the associated horn and friction tool at one end of the shoe toward or from the associated horn and friction tool at the other end in accordance with the length of the shoe.

14. In a platform cover turning machine, a support for a partially completed platform shoe having an unturned platform cover, means for

moving the support with a shoe thereon heightwise from and to an initial position, a turning horn engageable with the platform cover to turn the platform cover as the shoe is thus moved from initial position, a friction tool cooperating with the horn to turn the platform cover, and means actuated by the shoe support for automatically moving the friction tool into an operative position of engagement with the platform cover upon movement of the shoe support from initial position and for automatically moving the friction tool into an out-of-the-way position upon return of the shoe support to initial position. 10

15. In a platform cover turning machine, a support for a partially completed platform shoe having an unturned platform cover, means for moving the support with a shoe thereon to and from an initial position, a turning horn engageable with the platform cover to turn the platform cover as the shoe is thus moved from initial position, a friction tool cooperating with the horn to 20

turn the platform cover, a spring for urging the friction tool into operating position against the platform cover, a cam for holding the friction tool away from the platform cover, and means actuated by the shoe support for releasing the friction tool from said holding cam to permit the spring to move the friction tool into operative position when the shoe support has moved a pre-determined distance from its initial position. 5

JOHN T. LANCASTER.
